UNITED STATES PATENT OFFICE

LESTER P. BARLOW, OF DETROIT, MICHIGAN

FUEL-FEED SYSTEM FOR INTERNAL-COMBUSTION ENGINES OF AUTOMOBILES

Application filed October 2, 1929. Serial No. 396,891.

This invention relates to new and useful improvements in fuel feed systems for internal combustion engines of automobiles where-
in a pump is employed to draw fuel from a
5 main tank and force said fuel upwardly into an auxiliary or gravity tank from which the fuel is delivered by gravity to a carbureter lo-
cated at a level below said auxiliary tank.

Among the several objects of my inven-
10 tion are to provide a vacuum connection be-
tween the auxiliary or gravity tank and the
engine for drawing the initial charge of liq-
uid fuel into said auxiliary tank; to provide
means for controlling both the vacuum con-
15 nection and the air vent of the auxiliary tank
whereby during normal operations of the en-
gine the former will be closed and the latter
will be open to permit the pump to function,
and whereby upon movement of said control-
20 ling means the vacuum connection will be op-
ened and the air vent will be closed to thereby
subject the fuel feed connection between the
main and auxiliary tanks to the action of the
vacuum connection and effect a filling of the
25 auxiliary tank with fuel; to provide a control
valve in the auxiliary tank for automatically
closing the fuel inlet upon the fuel reaching
a predetermined level and for automatically
opening said inlet whenever said level drops;
30 to provide a by-pass in the pump for auto-
matically by-passing the fuel in the pump
whenever the fuel inlet valve of the auxiliary
tank is closed; to provide a check valve in the
feed connection between the auxiliary tank
35 and the carbureter for preventing air being
drawn into the tank from the carbureter when
the vacuum connection is open; to provide a
single manually operable valve for control-
ling the vacuum connection and the air vent
40 of the auxiliary tank, and to provide a suf-
ficient tolerance between said manually op-
erable valve and its seat to permit fuel vapors
in the auxiliary tank being carried off
45 through the vacuum connection when said
valve is in its normal position.

With these and other objects in view which
will more fully appear, the nature of the in-
vention will be more clearly understood by
50 following the description, the appended
claims, and the several views illustrated in
the accompanying drawings.

In the drawings:

Figure 1 is a more or less diagrammatic
view showing the application of my inven-
55 tion to an internal combustion engine of an
automobile,

Figure 2 is an enlarged vertical sectional
view through the auxiliary or gravity fuel
tank, the view showing the control valve in 60
normal position closing the vacuum connec-
tion and opening the air vent,

Figure 3 is a top plan view thereof,

Figure 4 is a top plan view of the float lo-
cated within the gravity tank and showing 65
particularly the manner of pivotally support-
ing the same,

Figure 5 is an enlarged detail section show-
ing the control valve in its moved or abnor-
mal position whereby the vacuum connec- 70
tion is open and the air vent is closed.

Figure 6 is a perspective view of the con-
trol valve, and

Figure 7 is a similar view but looking at
the valve from another angle. 75

Like reference numerals designate corre-
sponding parts throughout the several figures
of the drawings.

In the accompanying drawings, there is
shown an internal combustion engine A hav-
ing an intake manifold B, a carbureter C
operatively connected with the intake mani-
fold, a main fuel tank D for containing gaso-
line or other liquid fuel, an auxiliary or grav-
ity tank E which is located in a plane above 85
the carbureter C, and a pump F which is
preferably of the type shown in my patent
for improvements in rotary pumps, No.
1,738,345, Dec. 3, 1929.

The main fuel tank D is provided with the
usual air vent 5, and a pipe line or fuel con-
nection, connects the main tank D with the
carbureter C. This fuel connection includes
a pipe 6 which communicates with the main
supply tank D and with the suction side of 90
the pump F, a pipe 7 which communicates
with the discharge side of the pump F and
with the upper end of the auxiliary or gravity
tank E, and a pipe 8 which connects the bot-
tom of the auxiliary or gravity tank E with 95
100

the carbureter. A vacuum connection or pipe 9 is connected to the upper end of the auxiliary or gravity tank E and to the intake manifold B.

5 The tank E includes a bottom 10, a peripheral wall 11, and a removable cover 12. The cover 12 is provided with an enlarged portion 13 in which is formed a vertical opening 14. A nipple 15 is threaded into the upper end 10 of the opening 14 and is connected to the feed pipe 7 by a coupling 16. The opening 14 constitutes an inlet for the liquid fuel, and mounted in the lower end of this opening 14 is a bushing 17 forming a seat for a vertically 15 movable needle valve 18 having a pointed upper end 19 which cooperates with a vertical passage 20 in said bushing to open or close the fuel inlet, depending upon the position of the valve 18. A float 21 is pivotally mounted 20 as at 22 to a support 23 depending from the cover 12. This float supports the vertically movable valve 18, and functions to automatically maintain the liquid fuel within the tank E at a predetermined level therein.

25 The cover 12 is formed with a second enlarged portion 24 and formed therein is a vertically disposed opening 25 forming a seat for a vertically movable valve 26. The enlarged portion 24 is provided with a recess 27 in its periphery for receiving the end of the vacuum connection or pipe 9, and a passage 28 which is in open communication with the recess 27 and with the valve seat 25. Also formed in the enlarged portion 24 of 30 the cover is a passage or air vent 29 which communicates with the valve seat 25 and with the atmosphere. The valve 26 is formed on one side and between the ends thereof with a recess or passage 30, and the valve on the 35 other side is formed at its lower end with a recess or passage 31 extending downwardly to the bottom of the valve. In the normal position of the valve 26, as shown in Figure 2, the recess or passage 30 is in open communication with the vacuum connection 9, but is closed from communication with the interior of the tank E by reason of the lower portion 40 of the valve being disposed below the recess 30. In this normal position of the valve, 45 the recess or passage 31 forms open communication between the atmosphere and the interior of the tank E.

The valve 26 is held in its normal position by means of a coil spring 33 which is located 50 around the upper end of the valve between the cover 12 and an integral flange 34 formed on the upper end of said valve. The upper end of the valve is provided with a reduced portion having a vertical slot 35 formed 55 therein. In order to depress the valve 26 to its abnormal position, I have provided a manually operable bell crank lever 36 which is pivoted on a horizontal axis 37 mounted on the cover 12. The lever 36 includes an 60 operating arm 38 and a valve actuating arm

39, the latter being positioned within the slot 35 of the valve and having a sliding fit therein. Connected to the operating arm 38 is a link 40 which preferably extends rearwardly through the panel board 41 of the automobile and is provided at its rearward end with a pull knob 42. When the operator pulls the link 40, the bell crank lever 36 is rocked to move the arm 39 downwardly whereupon the valve 26 will be moved downwardly against the tension of the spring 33. Immediately upon release by the operator, the spring 33 will automatically return the valve to its normal position, and in this upward movement of the valve the lever 36 70 will be returned to its normal position. In order to limit the upward movement of the valve by the influence of the spring 33, I have provided the lever 36 with a stop shoulder 43 which is adapted to engage a stop surface 75 44 formed on the cover 12, as shown in Figure 1.

A check valve 45 is positioned in the feed pipe or connection 8 and seats in a direction toward the tank E so as to permit fuel to 80 gravitate through said pipe to the carbureter but preventing air and fuel being drawn upwardly from the carbureter into the tank E whenever the vacuum connection 9 is open.

During the normal or running operation 90 of the engine, the parts are in the position as shown in Figure 2, wherein the valve 26 closes the vacuum connection 9 and opens the air vent 29. The pump F, which is geared 95 to the engine in the usual manner, draws fuel from the main tank D and forces said fuel upwardly into the auxiliary or gravity tank E through the inlet 14, providing the liquid level has dropped below the predetermined 100 level thereof. As soon as the level has been 105 reached, the float 21 raises the valve 18 to close the fuel inlet 14. When the inlet valve 18 is thus closed, the pump cannot force any more fuel into the auxiliary tank E, the fuel drawn from the main tank E being by-passed 110 in the pump in the manner disclosed in my patent referred to above.

The vacuum produced by the engine is 115 employed to draw the initial charge of fuel into the gravity tank. By using the vacuum of the engine, I reduce the time which would otherwise be necessary to pump fuel to the auxiliary tank by the small pump. The pump being of small capacity, requires a 120 considerable period of time to force sufficient fuel into the tank to start the engine. In order for the pump to function, it is necessary to turn the engine either by an electric starter or by a hand crank, but either of these methods is slow in forcing the fuel into the auxiliary tank, whereas by employing the engine vacuum the auxiliary tank can be 125 quickly filled. Therefore, when it is desired to employ the engine vacuum, valve 26 is manually depressed against the tension of 130

the spring 33 so as to open the vacuum connection 9 with the interior of the auxiliary tank, and simultaneously close the air vent 29. The operator continues to hold the valve 26 in its depressed or abnormal position and consequently the engine vacuum will draw liquid fuel from the main tank into the gravity tank until a predetermined fuel level is reached within the tank at which time the valve 18 through the medium of the float 21 automatically closes the fuel inlet opening 14. It is immaterial that the operator continues to hold the valve 26 in its depressed position after the auxiliary tank has been filled to the predetermined level for the reason that the engine vacuum will not function because the fuel inlet 14 is closed as well as the air vent 29. Upon release of the pull knob 42 by the operator, the spring 33 will function to automatically return the valve 26 to its normal position, thereby closing the vacuum connection 9 and opening the air vent 29.

The automobile engine operates at a variable speed and the fuel pump when geared to the engine will have a correspondingly variable speed. Therefore, a pump when operating at a variable speed will increase or decrease the amount of liquid fuel being pumped and will also create a change in pressures. Although various means for by-passing excess fuel may be employed or special devices for regulating pressures may be employed, it is practically impossible to maintain an absolutely constant pressure of fuel in the carburetor. By using the gravity or auxiliary tank wherein the fuel level in the tank is maintained at a constant predetermined level, and by having said tank open to the atmosphere, a constant predetermined pressure in the carburetor is insured.

Systems heretofore employed which included a pump for forcing the liquid fuel to the carburetor, have been unable to avoid the introduction of air which is carried by the liquid fuel into the carburetor. An automobile under motion causes the liquid fuel in the main tank to surge and splash against the sides of the tank. This causes the fuel to be aerated and the small air bubbles are picked up by the fuel stream and carried through the pump to the carburetor with the result that it is impossible to obtain the proper fuel mixture at the carburetor jet. Furthermore, the tension of the pump on the liquid fuel being drawn from the main tank causes the generation of gas bubbles in the fuel stream and this condition is aggravated particularly during hot weather. These bubbles vary in length with the result that the free gas and air in the system may become so great as to cause pump failure and consequently engine failure. By discharging these vapors and air together with the liquid fuel into the auxiliary tank, which is normal-

ly open to the atmosphere, the vapor and air are released from the liquid stream, and consequently the liquid fuel when being discharged from the carburetor nozzle or jet is substantially free of air and vapor.

Furthermore, in fuel systems employing pumps, it quite often happens that foreign matter in the fuel will cause the pump valves, either the inlet or discharge valves, or a bypass valve, to fail to seat and this failure results not only in pump failure but also in engine failure. Immediate relief under these circumstances may be obtained by my invention as a result of the operator depressing the valve 26 so as to open the vacuum connection 9 and close the air vent 29. This causes the engine vacuum to draw the liquid fuel rapidly from the main tank through the pump and thereby wash the foreign particles from the pump valves. The valve 26 is fitted to its seat 25 with a tolerance sufficient to permit vapors being carried from the auxiliary tank into the vacuum connection 9. This is very important in that it prevents the fumes from passing into the passenger compartment of the car. This leak through the vacuum connection is much smaller in area than the air vent and consequently there is no tendency to lower the pressure in the auxiliary tank to any appreciable degree.

From the foregoing, it will be observed that means is provided for preventing fuel vapors from reaching the passenger compartment of an automobile by conducting such vapors into an engine where they are burned; that the engine vacuum is employed for priming the system; that when the engine vacuum is employed the pump valves may be washed to remove any foreign matter; that the air and gas bound pump may be relieved immediately; that a constant and predetermined pressure in the carburetor is obtained by maintaining a constant predetermined level in the auxiliary tank, and that the float valve in the auxiliary tank performs the double function (1) of preventing liquid fuel being drawn into the engine through the valve 26 by the engine vacuum, and (2) of preventing liquid fuel from being forced by the pump into the auxiliary tank above a predetermined level.

It will be also apparent that the carburetor C is a fuel container and that the auxiliary tank E is a fuel container; that one of these containers is provided with an air vent and is located in a fuel connection between the intake manifold and the main tank; that said connection includes the pump or its equivalent; that one of the containers is provided with a vacuum connection to the intake manifold; that valve means is provided in one of said containers for normally closing the vacuum connection and opening the air vent, and that means is provided for moving the

valve means to open the vacuum connection and to close the air vent.

It is, of course, to be understood that the details of structure and arrangements of parts may be variously changed and modified 5 without departing from the spirit and scope of my invention.

I claim:

1. In a fuel feed system, the combination 10 with an internal combustion engine having an intake manifold, of a carbureter connected to said manifold, a main supply fuel tank, a fuel feed connection between the main tank and the carbureter including a fuel pump and 15 an auxiliary fuel tank having an air vent, a vacuum connection between the auxiliary tank and the intake manifold, valve means for the auxiliary tank normally closing the vacuum connection and opening the air vent, and means for moving said valve means to 20 open the vacuum connection and close the air vent.

2. In a fuel feed system, the combination 25 with an internal combustion engine having an intake manifold, of a carbureter connected to said manifold, a main supply fuel tank, a fuel feed connection between the main tank and the carbureter including a fuel pump and 30 an auxiliary fuel tank having an air vent, a vacuum connection between the auxiliary tank and the intake manifold, valve means for the auxiliary tank normally closing the vacuum connection and opening the air vent, means for moving said valve means to open 35 the vacuum connection and close the air vent, and means for automatically returning said valve means to normal position upon release of said valve moving means.

3. In a fuel feed system, the combination 40 with an internal combustion engine having an intake manifold, of a carbureter connected to said manifold, a main supply fuel tank, a fuel feed connection between the main tank and the carbureter including a fuel pump and 45 an auxiliary fuel tank having an air vent, a vacuum connection between the auxiliary tank and the intake manifold, valve means for the auxiliary tank normally closing the vacuum connection and opening the air vent, and manually operable means including a 50 lever connected to the valve means for opening the vacuum connection and closing the air vent.

4. In a fuel feed system, the combination 55 with an internal combustion engine having an intake manifold, of a carbureter connected to said manifold, a main supply fuel tank, a fuel feed connection between the main tank and the carbureter including a fuel pump and 60 an auxiliary fuel tank having an air vent, a vacuum connection between the auxiliary tank and the intake manifold, valve means for the auxiliary tank normally closing the vacuum connection and opening the air vent, and manually operable means including a lever 65

connected to the valve means for opening the vacuum connection and closing the air vent, and means for automatically returning said valve means to normal position upon release of said valve moving means.

5. In a fuel feed system, the combination 70 with an internal combustion engine having an intake manifold, of a carbureter connected to said manifold, a main supply fuel tank having an air vent, a fuel feed connection between the main tank and the carbureter including a fuel pump and an auxiliary fuel tank having an air vent and a fuel inlet, the pump being disposed intermediate the tanks, a vacuum connection between the auxiliary 75 tank and the intake manifold, a control valve for the auxiliary tank cooperating with the fuel inlet for automatically closing said inlet when the fuel in the auxiliary tank reaches a predetermined level and for automatically 80 opening said inlet when the fuel drops below said level, a valve means in the auxiliary tank normally closing the vacuum connection and opening the air vent, and means for moving said valve means to open the vacuum connection and close the air vent.

6. In a fuel feed system, the combination 85 with an internal combustion engine having an intake manifold, of a carbureter connected to said manifold, a main supply fuel tank 90 having an air vent, a fuel feed connection between the main tank and the carbureter including a fuel pump and an auxiliary fuel tank having an air vent and a fuel inlet, the pump being disposed intermediate the tanks, a vacuum connection between the auxiliary 95 tank and the intake manifold, a control valve for the auxiliary tank cooperating with the fuel inlet for automatically closing said inlet when the fuel in the auxiliary tank reaches a predetermined level and for automatically 100 opening said inlet when the fuel drops below said level, a valve means in the auxiliary tank normally closing the vacuum connection and opening the air vent, means for moving said valve means to open the vacuum connection and close the air vent, and means for automatically returning said valve means to normal position upon release of said valve moving means.

7. In a fuel feed system, the combination 110 with an internal combustion engine having an intake manifold, of a carbureter connected to said manifold, a main supply fuel tank having an air vent, a fuel feed connection between the main tank and the carbureter including a fuel pump and an auxiliary fuel tank having an air vent and a fuel inlet, the pump being disposed intermediate the tanks, a vacuum connection between the auxiliary 115 tank and the intake manifold, a control valve for the auxiliary tank cooperating with the fuel inlet for automatically closing said inlet when the fuel in the auxiliary tank reaches a predetermined level and for automatically 120 opening said inlet when the fuel drops below said level, a valve means in the auxiliary tank normally closing the vacuum connection and opening the air vent, and means for automatically returning said valve means to normal position upon release of said valve moving means.

65 125 130

- opening said inlet when the fuel drops below said level, a single valve element in the auxiliary tank normally closing the vacuum connection and opening the air vent, manually operable means including a lever connected to the valve element for opening the vacuum connection and closing the air vent, and means for automatically returning said valve element to normal position upon release of said manually operable means.
8. In a fuel feed system, the combination with an internal combustion engine having an intake manifold, of a carbureter connected to said manifold, a main supply fuel tank having an air vent, a fuel feed connection between the main tank and the carbureter including a fuel pump and an auxiliary fuel tank having an air vent, a vacuum connection between the auxiliary tank and the intake manifold, a control valve for the auxiliary tank cooperating with the fuel inlet for automatically closing said inlet when the fuel in the auxiliary tank reaches a predetermined level and for automatically opening said inlet when the fuel drops below said level, the pump being operatively connected to the engine, a valve means in the auxiliary tank normally closing the vacuum connection and opening the air vent, and means for moving said valve means to open the vacuum connection and close the air vent.
9. In a fuel feed system, the combination with an internal combustion engine having an intake manifold, of a carbureter connected to said manifold, a main supply fuel tank having an air vent, a fuel feed connection between the main tank and the carbureter including a fuel pump and an auxiliary fuel tank having an air vent, a vacuum connection between the auxiliary tank and the intake manifold, a control valve for the auxiliary tank cooperating with the fuel inlet for automatically closing said inlet when the fuel in the auxiliary tank reaches a predetermined level and for automatically opening said inlet when the fuel drops below said level, the pump being operatively connected to the engine and having a by-pass automatically operable when the fuel feed connection is closed by the inlet controlling valve to bypass the fuel at the pump, a valve means in the auxiliary tank normally closing the vacuum connection and opening the air vent, and means for moving said valve means to open the vacuum connection and close the air vent.
10. In a fuel feed system, the combination with an internal combustion engine having an intake manifold, of a carbureter connected to said manifold, a main supply fuel tank, a fuel feed connection between the main tank and the carbureter including a fuel pump and an auxiliary fuel tank having an air vent, a vacuum connection between the auxiliary tank and the intake manifold, valve means for the auxiliary tank normally clos-
- ing the vacuum connection and opening the air vent, means for moving said valve means to open the vacuum connection and close the air vent, and a check valve in the fuel feed connection between the carbureter and the auxiliary tank and operable to prevent flow of fuel and air from the carbureter to the auxiliary tank when the vacuum connection is open.
11. In a fuel feed system, the combination with an internal combustion engine having an intake manifold, of a carbureter connected to said manifold, a main supply fuel tank, a fuel feed connection between the main tank and the carbureter including a fuel pump and an auxiliary fuel tank having an air vent, a vacuum connection between the auxiliary tank and the intake manifold, a single valve element mounted in a seat in the auxiliary tank and normally closing the vacuum connection and opening the air vent, and means for moving said single valve element to open the vacuum connection and close the air vent, the fit between the valve element and seat having sufficient tolerance to carry off vapors through the vacuum connection when the valve element is in its normal position.
12. In a fuel feed system, the combination of an internal combustion engine having an intake manifold, of a main supply fuel tank, a fuel container having an air vent, a fuel feed connection between the container and the main tank including a pump, a vacuum connection between the container and the intake manifold, valve means for the auxiliary tank normally closing the vacuum connection and opening the air vent, and means for moving said valve means to open the vacuum connection and close the air vent.
13. In a fuel feed system, the combination of an internal combustion engine having an intake manifold, of a main supply fuel tank, a fuel container having an air vent, a fuel feed connection between the container and the main tank including a pump, a vacuum connection between the container and the intake manifold, valve means for the auxiliary tank normally closing the vacuum connection and opening the air vent, means for moving said valve means to open the vacuum connection and close the air vent, and means for automatically returning said valve means to normal position upon release of said valve moving means.
14. In a fuel feed system, the combination of an internal combustion engine having an intake manifold, of a main fuel tank, a fuel container having an air vent and a fuel inlet, a fuel feed connection between the container and the main tank including a pump, a vacuum connection between the container and the intake manifold, the pump being located between the container and the main tank, a control valve for the container cooperating with the fuel inlet for automati-

- 5 cally closing said inlet when the fuel in the container reaches a predetermined level and for automatically opening said inlet when the fuel drops below said level, valve means in the auxiliary tank normally closing the vacuum connection and opening the air vent, and means for moving said valve means to open the vacuum connection and close the air vent.
- 10 15. A cover unit for a fuel container comprising the combination with a cover having a fuel inlet opening, a valve seat, a vacuum inlet opening communicating with the valve seat, and an air vent communicating with said valve seat, of a single valve mounted in said seat and normally closing the vacuum inlet opening and opening the air vent, and manually operable means mounted on the cover to move the valve to open the vacuum inlet opening and to close the air vent.
- 15 16. A cover unit for a fuel container comprising the combination with a cover having a fuel inlet opening, a valve seat, a vacuum inlet opening communicating with the valve seat, and an air vent communicating with said valve seat, of a single valve mounted in said seat and normally closing the vacuum inlet opening and opening the air vent, manually operable means mounted on the cover 20 to move the valve to open the vacuum inlet opening and to close the air vent, and a spring mounted on the cover and cooperating with the valve to return the same to its normal position upon release of said manually oper- 25 able means.

In testimony whereof I affix my signature.
LESTER P. BARLOW.
